(57) **CLAIM**

I claim the ornamental design for a screw top vessel closure, as shown and described.

DESCRIPTION

FIG. 1 is a front view of a screw top vessel closure showing our new design;

FIG. 2 is a back view of the screw top vessel closure of FIG. 1;

FIG. 3 is a left side view of the screw top vessel closure of FIG. 1;

FIG. 4 is a right side view of the screw top vessel closure of FIG. 1;

FIG. 5 is a top view of the screw top vessel closure of FIG. 1;

FIG. 6 is a bottom view of the screw top vessel closure of FIG. 1;

FIG. 7 is a perspective view of the screw top vessel closure of FIG. 1;

FIG. 8 is a perspective view of the screw top vessel closure of FIG. 1, with the closure in the closed position and the unclaimed vessel depicted in broken lines;

FIG. 9 is a perspective view of the screw top vessel closure of FIG. 1, with the closure in the opened position and the unclaimed vessel depicted in broken lines;

FIG. 10 is a view of a user opening the screw top vessel closure of FIG. 1, with the unclaimed vessel and the unclaimed user's hand depicted in broken lines; and,

FIG. 11 is a view of a user closing the screw top vessel closure of FIG. 1, with the unclaimed vessel and the unclaimed user's hand depicted in broken lines.

The broken lines in FIGS. 8-11 illustrating a vessel and a human user depict environment included to show the screw top vessel closure in various positions of use and form no part of the claimed design. All other broken lines and the spaces contained within them depict portions of the screw top vessel closure that form no part of the claimed design.
